Atty.

UNITED STATES PATENT OFFICE.

WILLIAM R. UHLEMANN, OF CHICAGO, ILLINOIS.

LENS-MOUNT.

1,323,994.

Specification of Letters Patent. Patented Dec. 2, 1919.

Application filed February 8, 1919. Serial No. 275,707.

To all whom it may concern:

Be it known that I, WILLIAM R. UHLEMANN, a citizen of the United States of America, and a resident of Chicago, in the county of Cook, State of Illinois, have invented certain new and useful Improvements in Lens-Mounts, of which the following is a specification.

This invention relates to finger piece eye-glass mountings adapted for use in connection with the non-metallic or shell rim type of eye-glasses, such shell rim being of a wholly non-metallic or a metal reinforced non-metallic structure, and the present improvement has for its object:—

To provide a substantial and effective structural formation and association of parts adapted to afford a very compact structure, capable of ready assemblage and subsequent disassemblage for repairs and replacements, and by means of which a very desirable close pupillarity of the lenses can be attained, all as will hereinafter more fully appear.

25 In the accompanying drawing:—

Figure 1 is a fragmentary perspective view illustrating the general arrangement of parts in a preferred form of the present invention.

30 Fig. 2 is a detail vertical section on line x^2-x^2 , Fig. 3.

Fig. 3 is a similar view in a plane at right-angles to the plane of Fig. 2, and on line x^3-x^3 , Fig. 1.

35 Fig. 4 is a detached perspective view of the connecting means for the ends of the split lens holding ring, the nose bridge, the supporting stem and spring of the finger piece mechanism of the eye-glass mounting.

40 Fig. 5 is a detail vertical section of a modification.

Like reference numerals indicate like parts in the several views.

Referring to the drawing, 1 designates 45 the usual arched bridge piece fixedly attached to the lens holding members and adapted to hold the same together in properly spaced relation.

2 designates one of the split lens holding 50 members or rings above referred to, and which in the present structure is formed of

a non-metallic substance, such as tortoise shell. In the carrying out of the invention the said members or rings 2, may be formed wholly of non-metallic material, or partly 55 by an outer portion of such non-metallic material and an inner metallic lens holding ring 3, as usual in the present type of mountings, and as hereinafter set forth in the detailed description of the invention. 60

4 designates one of the eye-glass lenses fitting an inner groove in the main lens holding member 2 or in the inner lens holding ring 3, as the case may be and as usual in this type of mountings. 65

In the construction shown in Figs. 1, 2, 3 and 4, the adjoining ends or terminals of the inner metallic lens holding ring 3 at the split thereof, are formed with outwardly disposed bars or extensions 5 to afford a substantial contact for the adjacent ends of the split ring 3. In turn said bars or extensions 5 are formed with angularly arranged bar or clip pieces 6 having an approximately parallel relation to the adjacent main portion of the ring 3 and separated therefrom by a space corresponding with the thickness of the non-metallic lens inclosing ring 3 aforesaid, and as shown said clip pieces 6 are provided with terminal prongs 7 adapted to engage in recesses in the ring 2 and attain a simple and substantial connection of the outer and inner lens rings 2 and 3 aforesaid. This construction is set forth and claimed in my companion application 85 Serial No. 275708 filed Feb. 8, 1919, and the point of novelty in the present application is accordingly confined to the combination and association of one of the portions or bars 5 with the finger piece mechanism hereinafter described in detail. 90

8 designates a sleeve member or shell fixedly attached to an end of the lens engaging ring 3 and its bars 5 and 6 as shown, and projecting beyond the same to constitute an inclosure for the central portions of the finger piece mechanism above referred to, and in addition to constitute a part of the fastening means by which the lens holding ring is secured in its contracted or assembled condition. 95

9 designates the pivot stem of the finger

piece mechanism above referred to, formed at its lower end with a screw-threaded portion adapted to screw into an orifice formed in the lowermost outwardly disposed bar 5 of the lens holding ring 3 aforesaid, while the upper end of said stem 9 is formed with a transverse orifice 10 for the passage of a transverse rivet or screw 11, which also passes through aligned orifices in the sleeve 10 member 8 aforesaid, to constitute the means by which the described parts are connected together in assembled relation and in a 15 substantial manner.

12 designates the finger piece member or lever pivoted at its mid-length on the stem 9 aforesaid, and having at its outer end the usual finger formation, while its inner end is provided with a nose grip member 13, as usual in finger piece mountings in general 20 use.

14 designates the spring by which the finger piece or lever 12 is actuated. Said spring is of any usual form and surrounds the stem 9 with one end adapted to engage 25 the lever 12, and the other end having engagement in an orifice or slot 15 in the sleeve 8, as shown more particularly in Figs. 3 and 4.

With the above described arrangement of 30 the finger piece or lever 12, pivot 9 and actuating spring 14 within the plane of the lens inclosing frame or ring, a very compact structure is provided so that a close pupillary 35 distance of the eye-glass lenses may be attained in an effective and convenient manner.

In the modified structure shown in Fig. 5' upper and lower sleeves 16 and 17 are secured directly to the respective ends of the non-metallic split lens holding member 2, 40 and are adapted to afford the supporting and inclosing means for the centrally arranged portions of the finger piece mechanism above described. The upper and lower sleeves 16, 17 receive the respective ends of 45 said non-metallic outer ring member 2 with the parts secured together by clip pieces or extensions 18, similar to the clip pieces 6 heretofore described and having likewise engagement in recesses in the outer surface 50 of the member 2, as shown.

Having thus fully described my said invention what I claim as new and desire to secure by Letters Patent, is:—

1. In an eye-glass mounting, the combination of a split lens inclosing ring provided with an outward extension on one of its ends, a nose bridge attached to said extension, a resilient finger piece mechanism carrying a nose grip and pivotally mounted 55 on said extension in adjacent relation to the inner surface of said ring and in a gap formed in the other end of said ring, and means for fastening the ends of said ring together, substantially as set forth.

2. In an eye-glass mounting, the combination of a split lens inclosing ring provided with an outward extension on one of its ends, a nose bridge attached to said extension, a sleeve attached to the other end of said ring, a resilient finger piece mechanism 60 carrying a nose grip and pivotally mounted within said sleeve, and means for fastening the ends of said ring together, substantially as set forth.

3. In an eye-glass mounting, the combination of a split lens inclosing ring provided with an outward extension on one of its ends, a nose bridge attached to said extension, a sleeve attached to the other end of said ring, a resilient finger piece mechanism 65 carrying a nose grip and pivotally mounted in said sleeve, a pivot stud mounted on the outward extension aforesaid, and affording pivotal connection for said finger piece mechanism, and a transverse screw intersecting the said sleeve and pivot stud, substantially as set forth.

4. In an eye-glass mounting, the combination of a split outer lens inclosing ring, an inner split lens holding ring having an outward extension at one of its ends, a nose bridge attached to said extension, a resilient finger piece mechanism carrying a nose grip and pivotally mounted on said extension in adjacent relation to the main portion of 95 said inner ring and located in a gap formed at the split of the outer ring aforesaid, and means for fastening the ends of said rings together, substantially as set forth.

5. In an eye-glass mounting, the combination of a split outer lens inclosing ring, an inner split lens holding ring having outward extensions at its ends, a nose bridge attached to one of said extensions, a sleeve attached to the companion extension, a resilient finger piece mechanism carrying a nose grip and pivotally mounted within 100 said sleeve, and means for fastening the ends of said rings together, substantially as set forth.

6. In an eye-glass mounting, the combination of a split outer lens inclosing ring, an inner split lens holding ring having outward extensions at its ends, a nose bridge attached to one of said extensions, a sleeve attached to the companion extension, a resilient finger piece mechanism carrying a nose grip and pivotally mounted in said sleeve, a pivot stud mounted on the first mentioned outward extension aforesaid and 115 affording pivotal connection for the aforesaid finger piece mechanism, and a transverse screw intersecting the said sleeve and pivot stud, substantially as set forth.

7. In an eye-glass mounting, the combination of a split outer lens inclosing ring, an inner split lens holding ring having outward extensions at its ends, a nose bridge 120

attached to one of said extensions, a sleeve attached to the companion extension, a resilient finger piece mechanism carrying a nose grip and pivotally mounted within said sleeve, clip pieces extending in opposite directions from said outward extensions and having terminal prongs adapted to engage in recesses in the outer lens inclosing ring, and means for fastening the ends of said rings together, substantially as set forth.

Signed at Chicago, Illinois, this 1st day of February, 1919.

WILLIAM R. UHLEMANN.
